TWO-WAY OPENING BELT

Raymond T. Crocker, San Francisco, Calif.

Application August 26, 1935, Serial No. 37,993

2 Claims. (Cl. 241—10)

My invention relates to improvements in two-way opening belts and it consists of the combinations, constructions and arrangements herein-after described and claimed.

Belts have been provided with name plates and they have also been provided with buckles, or other adjustable fastening means. In the present invention I provide a name plate for a belt, and the belt has means for removably securing it to the ends of the name plate. This permits the belt to be opened at the name plate if desired when removing the belt from the trousers. In addition the buckle can be used for adjusting the effective length of the belt, and can also be used for opening the belt.

The principal advantage of the two-way opening belt is that the wearer can dispose the name plate at the front of his trousers where it will be seen, or if desired the belt can be turned around in the trousers until the buckle or other fastening means is disposed at the front of the trousers. When the belt is in this position the name plate will be disposed at one side of the trousers and will be hidden from view. This permits the wearer to make the belt perform a double use. When the name plate is shown the belt can be used as a school belt or the like. When the buckle is shown the belt becomes a dress belt.

The belt is an improvement over my patent on a belt buckle issued June 8, 1926, No. 1,588,172.

Other objects and advantages will appear in the following specification, and the novel features of the device will be particularly pointed out in the appended claims.

My invention is illustrated in the accompanying drawing forming a part of this application, in which

Figure 1 is an isometric view of the belt showing the name plate and the buckle;

Figure 2 is a section along the line 2—2 of Figure 1 and illustrates the manner of removably securing the name plate to the belt; and

Figure 3 is a view of the buckle end of the belt.

In carrying out my invention I provide a belt consisting of a long strap A, a short strap B, a name plate C and a buckle or other suitable adjustable fastening means D. Figure 1 shows the buckle D disposed approximately ninety degrees away from the name plate C.

Referring to Figure 2 it will be noted that the strap A has its edge 1 abutting the edge 2 of the name plate C. A loop member 3 has one end 4 stitched at 5 to the strap A and has its other end passed through an opening 6 in the name plate C, and then secured to the inner surface

of the strap A by means of a snap fastener 7. This permits the loop 3 to be unfastened, and then removed through the slot 6, and thus the strap A can be detached from the name plate C.

The strap B is secured to the opposite end of the name plate C in the same manner. A loop 8 similar to the loop 3 is secured to the strap B and is passed through an opening 9 in the other end of the name plate C, and then the free end of the loop member is removably secured to the inner side of the strap B by a snap fastener 10. The name plate C is held in adjusted position between the straps A and B by the ends 1 and 11 of the straps A and B abutting the edges 2 and 12 of the name plate. In this way the name plate appears to form a continuous part of the belt.

The buckle D is shown in Figure 3 and is of standard construction. It is obvious that in place of the buckle any other type of fastening means may be resorted to such as a zipper, etc. The strap A has an end portion 13 passed through the buckle D and then stitched at 14. The end of the strap B has openings 15 therein and a tongue 16 of the buckle is designed to enter the desired opening 15, and thus alter the effective length of the belt. Loop members 17 slidably receive the end of the strap B.

From the foregoing description of the various parts of the device, the operation thereof may be readily understood.

The belt is designed primarily for schools and academies, etc., and when the belt is worn at the institutions the name plate C is disposed where it may be viewed. The buckle D will then be disposed at the side of the wearer and will not be visible. The buckle in this instance acts as an adjusting feature for altering the effective length of the belt. The belt is opened and closed by removing either of the loops 3 or 8 from the name plate.

When the belt is used for dress appearances the buckle or other suitable fastening device D is disposed where it may be viewed and this will swing the name plate C to the side of the wearer. The belt may now be opened in the usual manner by unfastening the buckle, and at the same time the buckle can be used for altering the effective length of the belt. It will be seen that the same belt can be used for two different occasions and that only the desired portion of the belt may be disposed in a position for view. The other part will be hidden by the coat of the wearer.

While I have shown only the preferred form of my invention, it should be understood that various

changes or modifications may be made within the scope of the appended claims without departing from the spirit of the invention.

I claim:

- 5 1. A belt comprising a two-part strap which has a buckle at one end and a series of holes in the other end, one of which is fitted upon the tongue of the buckle to make an adjustment of comparative permanence, a plate establishing the continuity of the two-part strap, and connecting means between the ends of the plate and the adjacent strap ends, at least one of the connecting means including a glove fastener which enables the instantaneous opening of the
- 10

belt without spoiling the adjustment at the buckle.

2. A combination school and dress belt comprising a main back strap having a buckle on one end and a loop with a glove fastener on the other end, a lesser front strap also having a loop and a glove fastener at one end, a single-piece plate situated between the two straps and having integral end bars to which the respective loops are separably attached by means of the glove fasteners, the other end of the front strap having a series of holes to adjustably receive the tongue of the buckle.
